(57) **CLAIM**

The ornamental design for a wearable weight, as shown and described.

DESCRIPTION

FIG. 1 is a top view of the wearable weight according to a first embodiment of the new design;

FIG. 2 is a front view of the wearable weight of FIG. 1;
FIG. 3 is a bottom view of the wearable weight of FIG. 1;
FIG. 4 is a rear view of the wearable weight of FIG. 1;
FIG. 5 is a left side view of the wearable weight of FIG. 1;
FIG. 6 is a right side view of the wearable weight of FIG. 1;
FIG. 7 is an enlarged partial section view of the wearable weight taken along section line 7-7 of the endcap shown in FIG. 5;

FIG. 8 is an enlarged partial section view of the wearable weight taken along section line 8-8 of the endcap shown in FIG. 6;

FIG. 9 is a top view of a wearable weight according to a second embodiment thereof;

FIG. 10 is a front view of the wearable weight of FIG. 9;
FIG. 11 is a bottom view of the wearable weight of FIG. 9;
FIG. 12 is a rear view of the wearable weight of FIG. 9;
FIG. 13 is a left side view of the wearable weight of FIG. 9;
FIG. 14 is a right side view of the wearable weight of FIG. 9;

FIG. 15 is an enlarged partial section view of the wearable weight taken along section line 15-15 of the endcap shown in FIG. 13; and,

FIG. 16 is an enlarged partial section view of the wearable weight taken along section line 16-16 of the endcap shown in FIG. 14.

The broken lines in the drawings illustrate portions of the wearable weight that form no part of the claimed design. The appearance of any portion of the wearable weight shown between the break lines forms no part of the claimed design.
